UNITED STATES PATENT OFFICE.

BURDICK A. STEWART, OF PITTSFIELD, MASSACHUSETTS.

SECTIONAL PLASTIC STEP.

1,293,233.

Specification of Letters Patent.

Patented Feb. 4, 1919.

Application filed April 10, 1917. Serial No. 160,949.

To all whom it may concern:

Be it known that I, BURDICK A. STEWART, a citizen of the United States, residing at Pittsfield, in the county of Berkshire and 5 State of Massachusetts, have invented certain new and useful Improvements in Sectional Plastic Steps, of which the following is a specification.

This invention relates to sectional plastic 10 steps and concerns an improved method of constructing and assembling the same.

A principal object is the provision of steps constructed of separately formed parts susceptible of manufacture in quantity, as 15 standardized stock articles for trade and commerce. A further object is the provision of steps which may be assembled for use, or disassembled for repairs, without the need of skilled labor or special tools.

20 Referring to the accompanying drawings wherein I have illustrated the above described method of constructing concrete steps and a preferred form of embodiment thereof,—

25 Figure 1 is a front elevation of a series of concrete steps assembled for use;

Fig. 2, a vertical section of the same on the line A—A of Fig. 1;

30 Fig. 3, a detail section embracing a portion of one of the upright supports, showing the form and arrangement of one of the pockets or recesses for the studs;

Fig. 4, an edge view of the portion of the 35 upright support shown in Fig. 3;

Fig. 5, a bottom view of one of the stud sockets provided in the lower face, and

Fig. 6, a plan side view of the same.

As shown, the step in assembly forms a 40 hollow unitary structure formed of separate plastic slabs detachably secured together and constructed of preferably solid concrete previously prepared in suitable molds provided for the purpose. The structure comprises a series of alternate risers 6, 7, etc., and treads 4, 5, etc., fitted to oppositely arranged upright supports forming end-pieces 1, 3, and an intermediate support 2. The top tread 4 forms an extended platform, preferably wider than the lower treads, in conformity with the usual practice.

The several treads and risers are serially connected in detachable relation to each other by removable rods 21, and are independently connected by rods or studs 13 to the upright supports 1, 2, 3, the rear margin

of each tread being extended under and secured to the overlying riser. Although each piece may be separately attached and detached to the upright supports independently of the remaining pieces, in assembling the usual and preferred practice is to attach the pieces in regular order, commencing with the lowest riser 7. The studs 13 securing this part, like the remaining risers 6, 6, to the upright supports, carry on their rear or lower ends a nut 15 and terminate in lateral pockets 16 opening on one side of the upright supports. The pockets 16 communicate by a suitable bore 22, extended centrally through the body of the upright supports, 60 with metallic sockets 10 embedded on the inner face of the risers. These sockets 10 are set in rigid position in the concrete and have a flanged head 23 which prevents displacement, and a threaded central recess 24 65 to receive one end of the studs 13, which are also threaded.

The rods 21 securing the treads and risers together are constructed similar to the studs 13, carrying at their lower ends a nut 11 and 70 terminating at their upper ends in a socket 9, similar to the socket 10, above described, said rods being extended through a suitable opening provided centrally vertically 75 through the riser and transversely through the rear end of the tread.

I have further shown and preferably provide a horizontally arranged tie-piece 8 in the rear, similar in formation to the risers, said tie-piece being bolted to the top tread 4 80 by a series of rods 18, secured in the manner of the rods 21, and to the upright supports 1, 2, 3, by studs 13. This tie-piece is designed to strengthen the frame work of the structure by securing the upright supports 90 in rigid position in the rear.

The lower riser 7, and preferably also the tie-piece 8, is provided on its lower edge with suitable recesses 17 for the reception of the nuts 11 on the rods 21.

100 While I have illustrated the use of an intermediate or auxiliary upright support 2, it will be understood that the use of this additional support is not necessary in steps of short length.

I claim:

A sectional plastic step comprising oppositely arranged upright supports having lateral pockets therein; treads and risers serially arranged on said supports, each of 110

2

said risers being arranged for support on the rear margin of the underlying tread; and securing means for locking the several sections together in detachable relation and comprising metallic sockets seated in the treads and risers, rods secured at one end in said sockets and projecting at the opposite end into the upright supports and

terminating in said pockets, and securing members carried on the rods in said pockets. 10

In testimony whereof I hereunto affix my signature in presence of two witnesses.

BURDICK A. STEWART.
